No. 859,986.

PATENTED JULY 16, 1907.

E. G. SMITH.
CLOTHES HANGER.
APPLICATION FILED NOV. 26, 1906.

UNITED STATES PATENT OFFICE.

ERNST G. SMITH, OF COLUMBIA, PENNSYLVANIA.

CLOTHES-HANGER.

No. 859,986.

Specification of Letters Patent.

Patented July 16, 1907.

Application filed November 26, 1906. Serial No. 345,127.

To all whom it may concern:

Be it known that I, ERNST G. SMITH, a citizen of the United States, residing at Columbia, in the county of Lancaster and State of Pennsylvania, have invented a new and useful Clothes-Hanger, of which the following is a specification.

This invention relates to clothes hangers or holders of that general type employed in laundries for carrying collars, cuffs or other articles of apparel through the 10 dry room.

In the operation of these devices much difficulty has been experienced in constructing a holder which would hold the garments properly in place when subjected to the action of the hot air blast within the dry room, and yet, at the same time, be of such construction as to permit of the ready and rapid hanging of the 15 clothes and stripping of the same from the holder.

In carrying out the present invention, the principal object is to provide a holder of such nature that the articles may be hung thereon without using both hands, the holder being usually made double, and being of such construction that the attendant is free to use both hands in simultaneously placing the articles on the 20 holder.

25 A further object of the invention is to provide a holder which will positively lock and will hold the articles in place when subjected to the action of the air blast.

A still further object of the invention is to provide 30 a holder from which the articles may be readily stripped, and which when stripped will be positively locked in open position.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details 35 of the structure may be made without departing from the spirit or sacrificing any of the advantages of the invention.

In the accompanying drawings:—Figure 1 is a perspective view of a clothes holder constructed in accordance with the invention. Fig. 2 is a rear elevation of the same showing the holder in position within its carrier. Fig. 3 is a side elevation showing the means for opening the holder and the stripper which serves also as a means for moving the parts to open locked position. 45 Fig. 4 is a view looking from the side opposite that shown in Fig. 3, showing the means for releasing the holder and allowing it to assume its closed locked position.

Similar numerals of reference are employed to indicate corresponding parts throughout the several figures 55 of the drawings.

The upper portion of the holder is made as usual, and includes a link member *a*, and a hanger bar *b* which carries a small shaft *c* on which are mounted wheels or disks *d* that travel in a track way *e*. The link *a* forms 60 a part of an endless link belt which is engaged and driven by suitable sprocket wheels in order to carry the several clothes holders or hangers into and through the dry room.

Depending from the link *a* is a hanger bar 10 carrying 65 a pair of laterally extended arms 11, from the rear face of which project clothes hooks or arms 12, these being preferably made of slightly bent pieces of wire adapted to pass through the button holes of collars, cuffs or other garments.

70 The hanger bar 10 further carries a pair of laterally extending arms 15 to which are pivoted a pair of arms 16, the latter forming part of a U-shaped bar 17, from the central portion of which depends an arm 18, and extending laterally from both sides of the arm 18 are 75 additional arms 19 that are provided with openings 20 adapted to receive the rear ends of the clothes hanging wires or arms 12. The arm 18 is extended below the arms 19, forming a tongue 21 that is adapted to engage with a stripper bar 22, the latter being generally in the 80 form of approximately U-shaped bar, as will be seen on reference to Fig. 2, this stripper being usually located at a point outside the dry room.

85 The hanger bar 10 is further provided with a pin 24 on which is mounted a locking lever 25. The rear end 85 of this lever is extended rearward and downward and is provided with an inclined slot 26, at the base or bottom of which are two notches 27 and 28 separated from each other by a small lug 30. When the bar 17 is entered in the notch 27, as indicated in Fig. 1, the 90 guard arm 19 cannot move outward from the clothes hanging wires or arms 12, and thus forms a positive locking means which will prevent the articles of clothing from falling during the transit of the holders to the dry room. When the bar 17 is entered in the notch 28, 95 as indicated in Fig. 4, the guard arms 19 will be positively locked in open position, so that the articles of clothing can be readily placed on the wires or arms 12.

At a point slightly in advance of the stripper 22 is a roller 33 which is arranged to engage an arm 34 projecting from the upper end of the locking lever, and when the clothes holder arrives in the position shown in Fig. 3, this arm 34 will be engaged by the roller and will be moved to the position indicated, so that the bar 17 will be forced out of the notch 27, and at the 100 same time the front wall of the slot 26 by bearing 105

against the front face of the bar 17 will move the guard bars 19 outward to free the wires or arms 12. This operation occurs just slightly in advance of the completion of the movement of the wires or arms 12 across the 5 stripper, so that the holder will be moved to open position and the stripper may readily remove the articles of clothing from the wire without danger of tearing.

As the parts continue to move in the direction indicated by the arrow in Fig. 3, the lower tongue will 10 come into engagement with the cross bar of the stripper, and the bar 17 will be forced upward slightly to such position that it will enter the notch 28, and then assuming the position indicated by dotted lines in Fig. 3 and full lines in Fig. 4. In this position it will be 15 observed that the article carrying wires or arms 12 are perfectly free, and the articles may be placed thereon by using one hand only, as distinguished from devices of the ordinary class where the attendant is compelled to use one hand to open the holder and the other to 20 place the article of clothing in position thereon.

The articles of clothing are hung on the wires before the holder enters the dry room, and immediately after the article is placed in position, the arm 34 comes into contact with a second roller 40, and is slightly depressed, 25 so that the rear end of the locking lever is elevated and the guard arms are free to fall by gravity to locked position. In moving toward this position, the bar 17 will engage with the front wall of the slot 26, and will carry the locking lever down, this movement being 30 assisted by the superior weight of the rear of the locking lever, so that the parts will automatically assume the locked position indicated in Fig. 1, and will remain positively locked during the movement of the holder through the dry room.

35 The device possesses superior advantages in that it is positively locked in both open and closed positions, thus preventing the falling of any articles from the holder to the floor of the dry room, and at the same time maintaining the holder when outside the dry 40 room in such position that the attendant may use both hands and simultaneously attach two articles of clothing to each holder.

I claim:-

1. A clothes holder having a clothes suspending member, a pivotally mounted guard for said member, and locking means for securing the guard against accidental dis- 45 placement.

2. A clothes holder having a clothes suspending arm, a pivotally mounted guard therefor, and a locking member 50 for holding the guard in both open and closed positions.

3. A clothes holder having a clothes suspending arm, a guard therefor, and a locking lever engaging said guard and having two locking positions, one to retain the guard open, and the other to retain the guard closed.

55 4. A clothes holder having a clothes suspending arm, a guard therefor, a carrying bar for the guard, and a locking lever having a pair of notches into which said bar may enter, one to hold the guard in open position, and the other to hold the guard in closed position.

5. A clothes holder having a clothes suspending arm, a pivotally mounted guard having an opening for the reception of said arm, and a locking lever having a pair of locking notches, one for holding the guard in open position and the other for holding the guard in closed position. 60

6. A clothes holder having a clothes suspending arm, a guard having an opening for the reception of said arm, a pivotally mounted bar supporting the guard, and a pivoted locking lever having a pair of locking notches for the reception of said bar. 65

7. A clothes holder having a clothes suspending arm, a guard therefor, a carrying bar for the guard, a pivotally mounted locking lever having at one end a slot for the reception of the bar, the end wall of the slot being provided with a plurality of notches for the reception of the bar, and serving to retain the guard in both open and closed 75 position. 70

8. A clothes holder having a clothes suspending arm, a guard therefor, a pivotally mounted bar carrying the guard, a locking lever having at its rear end an inclined slot for the reception of the bar, one wall of the slot co-acting with the bar in movement of the parts to open and closed positions, the end wall of the slot having a pair of notches for the reception of the bar. 80

9. In apparatus of the class described, a clothes holder including a hanger arm, two pairs of arms extending laterally therefrom and arranged one above the other, clothes suspending wire projecting rearwardly of the lower arms, a U-shaped bar pivoted to the upper arms and provided with a depending arm, a pair of guards extending from the arm and provided with perforations for the reception of the wires, and a pivotally mounted locking lever carried by the hanger and provided with a pair of locking notches for the reception of said bar. 85

10. In apparatus of the class described, a clothes holder, an endless carrier therefor, a clothes suspending arm on said holder, a guard for said arm, a locking lever for the guard, a pair of lever engaging members, one for moving the same to open position, and the other to closed position, and a stripper coacting with the guard to move the latter to locked open position. 95

11. In apparatus of the class described, a clothes hanger having a clothes suspending arm, an endless carrier for the hanger, a guard for said arm, a locking lever for the guard, and means arranged in the path of the locking lever for moving said lever to released position, the lever 105 serving to move the guard to open position.

12. In apparatus of the class described, a clothes hanger having a clothes suspending arm, an endless carrier therefor, a guard for said arm, a carrying bar for the arm, a locking lever having a slot for the reception of the bar, one wall of the slot serving by engagement with said bar to move the guard to open position, the inner wall of the slot having a pair of notches for the reception of the bar, a stripper for the removal of the clothing from the arm, means in the path of movement of the lever for engaging the same and effecting movement to release position, and movement of the guard to open position, the stripper serving by engagement with said guard to move the latter to locked open position, and a stationary means also in the path of the lever for moving the same to released position, thereby allowing the guard to move by gravity to closed locked position. 110

In testimony that I claim the foregoing as my own, I have hereto affixed my signature in the presence of two witnesses.

ERNST G. SMITH.
